(57) **CLAIM**

The ornamental design for a wall sconce, as shown and described.

DESCRIPTION

FIG. 1 is a perspective view of the wall sconce according to the present invention;

FIG. 2 is a top view of the wall sconce shown in FIG. 1;
FIG. 3 is a bottom view of the wall sconce according to the present invention;

FIG. 4 is a front view of the wall sconce according to the present invention;

FIG. 5 is a back view of the wall sconce according to the present invention;

FIG. 6 is a left view of the wall sconce according to the present invention; and,

FIG. 7 is a right view of the wall sconce according to the present invention; the left side being a mirror image thereof.
The broken lines shown are for illustrative purposes only and form no part of the claimed design.
